CLAIM

The ornamental design for: a hair color applicator as shown, and described.

DESCRIPTION

FIG. 1 is a perspective view of a hair color applicator showing my new design,

FIG. 2 is a top side elevational view, a bottom side elevational view being a mirror image thereof;

FIG. 3 is a left side elevational view thereof;

FIG. 4 is a right side elevational view thereof;

FIG. 5 is a front elevational view; and,

FIG. 6 is a rear elevational view.

The broken lines are for environmental purposes only and form no part of the claimed design.

The hair color applicator in FIGS. 2–4 is shown broken away to show indeterminate length and for ease of illustration.
